(57) **CLAIM**

The ornamental design for a table top lighting control, as shown and described.

DESCRIPTION

FIG. 1 is a front elevational view of a table top lighting control showing our new design;

FIG. 2 is a top plan view thereof;

FIG. 3 is a bottom plan view thereof;

FIG. 4 is a left side elevational view thereof;

FIG. 5 is a right side elevation view;

FIG. 6 is a rear elevational view thereof; and,

FIG. 7 is a top, right front perspective view thereof.

The structural features depicted by broken lines have been shown for the purpose of illustrating portions of the table top lighting control that form no part of the claimed design.

1 Claim, 2 Drawing Sheets
